POTHEAD DEVICE

Filed June 3, 1929

UNITED STATES PATENT OFFICE

PEARSON F. WILLIAMS, OF CHICAGO, ILLINOIS, ASSIGNOR TO G & W ELECTRIC SPECIALTY CO., OF CHICAGO, ILLINOIS, A CORPORATION OF ILLINOIS

POTHEAD DEVICE

Application filed June 3, 1929. Serial No. 367,884.

This invention relates to pothead devices for the connection of electrical conductors in general, and more particularly for the connection of electrical cables and overhead conductors.

The primary object of this invention is to provide, in a pothead or similar device, a floating or axially adjustable contact for one of the conductors.

Other and further objects of this invention will be apparent as the same becomes better understood from an examination of the specification and claims in connection with the accompanying drawings, wherein:

Fig. 1 is a vertical section of a single conductor pothead embodying this invention;

Fig. 2 is a section taken at the line 2—2 of Fig. 1; and

Fig. 3 is a view similar to Fig. 1 of a modification.

Referring to the drawings more particularly, reference character 4 designates a lower tubular insulator member provided with a suitable mounting device 5 consisting of a metallic cup-shaped member enclosing the lower portion of the member 4 and secured to a supporting bracket 6, which may be attached to some supporting means.

A cable 7 extends upwardly through the bottom of the member 4 and is held therein by suitable clamping devices, for example, those shown in Patent No. 1,494,202 of P. F. Williams dated May 13, 1924.

A terminal or stem 8 is supported within the hollow tubular member 4 and is provided with a smooth cylindrical upper portion 9 projecting above said member 4, which portion acts as a terminal for the cable 7 which is slidably connected to the stem 8 through

the intermediary of a cylindrical extension 11 on the upper end of said cable which fits within a corresponding recess 12 in the lower end of said stem. The stem 8 is provided with an integral collar 13, which is seated in

a recess in an annular supporting member 14 and clamped in position by a circular ring 15 threaded to said supporting member. This supporting member 14 is held against a shoulder in the member 4 by means of a ring

16 cemented therein. Insulating disks 17 are

held on the upper end of the member 4 by a nut 18 threaded to the stem 8.

A cap 19 of insulation material, is provided with an inner chamber 21 and depending skirt 22 adapted to overlap the upper end of the member 4, and is carried by a connecting device 25 adapted to engage the terminal 9 for connecting the cable 7 with an overhead conductor 26 connected to the device 25. The conductor 26 is provided with an end 27 which extends and is secured into a recess in the upper end of a bolt 28. The bolt 28 is seated in a suitable opening in alignment with the cap 19 and is provided with a threaded shank 29 in threaded engagement with a cylindrical supporting member 31 of the device 25 for supporting the same.

The device 25 includes a sleeve 32 which forms a floating or axially adjustable contact between said device and the terminal 9 and is formed of two similar longitudinal sections 33 and 34 respectively, each adapted to cover nearly 180° of the periphery of said terminal and cooperating, when pressed together, to grip the same. The member 31 is provided with a pair of integral depending arms 35 which act to support an integral annular extension 36 which surrounds the sleeve 32 and is adapted to resiliently and pivotally connect therewith by means of a pair of oppositely disposed springs 37. These springs are each pivoted by means of a pin 38 to one wall of the annular extension 36 and are provided with oppositely and inwardly extending ends, each engaged in suitable recesses in the respective sections 33 and 34 for compressing the sections against the terminal 9 to form a floating contact therewith.

In addition to the pivotal and yieldable mechanical connection between the sleeve 32 and the annular extension 36 just described, which connection is substantially a universal connection, said sleeve and extension are electrically connected together in such a manner as to permit of the device having substantially the same current carrying capacity as the conductors connected thereby. This electrical connection comprises four copper braided members 39, attached by means of screws 41 centrally of their ends at equally spaced

positions on the periphery of the annular extension 36. The opposite ends of the respective conducting members 39 are attached to the corresponding ends of the sleeve 32 by means of screws 42, two of said members 39 serving to connect the extension 36 with the section 33 of the sleeve and the other two of said members 39 serving to connect said extension with the section 34 of said sleeve.

10 In the modification shown in Fig. 3, there is illustrated a device 43 which is identical with the device 25, just described, and which likewise includes a sleeve 33 for forming a floating contact.

15 In this modification the supporting member 45 for the connecting device is threaded to the upper end of a stem 46 of a pothead. In this instance the stem 46 and support is substantially the same as the stem 13 and support therefor in the previous embodiment, the exception being that in this case the upper end of the stem is threaded for connection to the member 45.

20 A conductor 47 has its end secured in the upper end of a plug 48. The plug 48 has its upper end secured in an annular insulating member 49 and is adapted to extend into the sleeve 44 for electrically connecting the conductor 47 with the cable (not shown) which is secured to the lower end of the stem 46.

25 The advantages of the connecting devices 25 and 43 in the aforescribed combinations of pothead devices will be apparent without further description.

30 I am aware that many changes may be made without departing from the principles of this invention and I, therefore, do not wish to be limited to the details shown or described.

What I claim is:

40 1. In a device of the character described, in combination with a pothead, of a pair of insulator members and conductors thereon, a rigid member adapted to embrace a conductor on one of the members, a member electrically connected to a conductor on the other insulator member and also flexibly connected to said embracing member, and a substantially universal mechanical connection between said electrically connected member and said embracing member said universal connection including bow springs.

45 2. In a device of the character described, in combination with a pothead, of a pair of insulator members and conductors thereon, a rigid member adapted to embrace a conductor on one of the members, a member electrically connected to a conductor on the other insulator members and also electrically connected to said embracing member, and a yieldable mechanical connection between said electrically connected member and embracing member.

50 3. In a device of the character described, in combination with a pothead, of a pair of insulator members and conductors thereon, a

rigid member adapted to embrace a conductor on one of the members, a member electrically connected to a conductor on the other insulator member and also electrically connected to said embracing member, and a substantially universal yieldable connection between said electrically connected member and embracing member.

55 4. In a device of the character described, the combination of a pair of insulator members and conductors thereon, an expandible member adapted to embrace a conductor on one of said insulator members, a member electrically connected to a second conductor on the other insulator member and also electrically connected to said expandible member, and a connection between said electrically connected member and said expandible member for resiliently connecting them together and for causing the expandible member to yieldingly engage the conductor embraced thereby for connecting the conductors on said insulator members together.

60 5. In a device of the character described, the combination of a pair of insulator members and conductors thereon, an expandible member adapted to embrace a conductor on one of said insulator members, a member electrically connected to a second conductor on the other insulator and also electrically connected to said expandible member, an annular extension on said electrically connected member surrounding the expandible member, and a pair of oppositely disposed springs between said extension and expandible member for causing the latter to embrace the conductor therein for connecting the conductors on said insulator members together.

65 6. In a device of the character described, the combination of a pair of insulator members provided with conductors, an expandible member adapted to embrace a conductor on one of the insulator members, a member electrically connected to a second conductor on the other insulator member and also electrically connected to the expandible member, an annular extension on the electrically connected member surrounding the expandible member, and a pair of oppositely disposed springs between said extension and expandible member pivotally and yieldingly connecting said extension and expandible member for causing the latter to embrace the conductor therein to thereby connect the conductors on said insulator members.

70 7. In a device of the character described, the combination of a pair of insulator members and conductors thereon, a tubular expandible member adapted to embrace a conductor on one of the insulator members, a member electrically connected to another conductor on the other insulator member and electrically connected to the expandible member, and means for pivotally connecting said

expansible member and electrically connected member together.

8. In a device of the character described, the combination of a pair of insulator members and conductors thereon, a tubular expansible member adapted to embrace a conductor on one of the insulator members, a member electrically connected to a second conductor on the other insulator member also electrically connected to the expansible member, and means for pivotally and yieldingly connecting the electrically connected and expansible member together.

9. A pothead comprising a pair of insulator members having conductors extending therefrom, a rigid member adapted to embrace a conductor on one of the members, a member electrically connected to a conductor on the other insulating member and also electrically connected to said embracing member, a substantially universal yieldable connection between said electrically connected member and embracing member, said universal connection including a ring member, bow springs mounted thereon and a split tubular member adapted to be supported thereby.

10. In pothead construction, the combination of male and female insulating members, cables extending from each member, a rigid cable terminal member projecting upwardly from the top of said male insulating member, a rigid tubular terminal member extending downwardly from said female member, a ring member resiliently carried thereby, said rigid terminal member adapted to telescopically engage therein to form a mechanical connection therebetween, and an electrical connection between said ring member and said tubular terminal member capable of carrying a surge of current equal to that carried by the cables.

11. In pothead construction, the combination of male and female insulating members, cables extending from each member, a rigid cable terminal member projecting upwardly from the top of said male insulating member, a rigid tubular terminal member extending downwardly from said female member, a split ring member resiliently carried thereby, said rigid terminal member adapted to telescopically engage therein to form a mechanical connection therebetween, and an electrical connection between said ring member and said tubular terminal member capable of carrying a surge of current equal to that carried by the cables.

12. A pothead connector comprising male and female insulating members, cables extending from each member, a rigid cable terminal member extending upwardly from the top of said male insulating member, a rigid tubular terminal member extending downwardly from said female member, a cylindrical spring member resiliently carried there-

by, said rigid terminal member adapted to telescopically engage therein, and an electrical connection between said spring member and said tubular terminal member capable of carrying a surge of current equal to that carried by the cables.

In witness whereof, I hereunto subscribe my name this 28 day of May, A. D. 1929.
